Attorney

UNITED STATES PATENT OFFICE.

MAX C. RICHARDSON, OF CANTON, OHIO, ASSIGNOR, BY MESNE ASSIGNMENTS, TO THE HOOVER COMPANY, OF NORTH CANTON, OHIO, A CORPORATION OF OHIO.

DUST-BAG SUPPORT.

Application filed May 27, 1922. Serial No. 564,125.

To all whom it may concern:

Be it known that I, MAX C. RICHARDSON, a citizen of the United States, residing at Canton, in the county of Stark and State of Ohio, have invented certain new and useful Improvements in Dust-Bag Supports, of which the following is a specification.

The object of my invention is to provide a dust-bag for portable vacuum cleaners having improved means for suspending the bag from the handle.

In these dust-bags, as formerly made, an example of which is shown in Patent No. 1,380,907, the loop by which they are attached to the handle, has been attached to the center of the bag-head. A dust-bag of such construction has several inherent disadvantages in that, when the bag is not inflated and the handle is in operative position, the bag crumples badly and sags down on the floor, thus causing undue wear on the bag at points where it falls in folds and where it contacts with the floor.

These difficulties are caused by the fact that to suspend the bag from the center of its head necessitates the use of a suspension-loop of a length equal to the radius of the bag so that when the bag is inflated it may hang freely below the handle. The effect of this is that when the bag is deflated the suspended length is the length of the bag plus the length of the loop and it is this excessive length which causes the crumpling and sagging mentioned above.

I attain the object of my invention by the structure illustrated in the accompanying drawing in which—

Figure 1 shows an inflated bag having my improved strap suspension, the handle being in operative position, and

Figure 2 is a deflated bag having my improved strap-suspension, the handle being in inoperative position.

Similar reference numerals refer to similar parts in the two figures.

My invention consists of a dust-bag 1 formed as shown, having side-walls 2 and a head 3. The suspension-member 4 is attached not as a loop but as a strap, that is, one end is attached adjacent to the center of the bag head at 5, and the other end is secured adjacent the periphery of the head at 6 on the side nearest the handle.

The lower end of the bag is provided with a bag-ring 7 which is adapted to be removably attached to the discharge opening of a suction-cleaner 8 by means of thumb-nuts 9.

A handle 10 is pivotally attached to the cleaner 8 at 11 and is provided intermediate its ends and on the under side with a bag slider-bar 12.

Means for suspending the upper end of bag 1 from the slider-bar 12 is provided comprising a member 13 formed at one end with a closed ring which is received on the slider-bar 12 and is adapted to move freely along the length thereof. The other end is provided with a substantially-closed ring in which the bag suspension-member 4 is slidably received.

Thus a construction is secured in which when the bag is deflated, the handle being in operative position, it will be prevented from sagging as with the old form since the bag will be suspended from about the point where the strap is attached to the periphery of the head. It is to be noted that this construction does not interfere with the movement of the handle to an inoperative or substantially-vertical position, since during such movement the strap slides through the substantially-closed ring portion of member 13 and acts substantially as a loop and supplies the length necessary for such movement and necessitated by the eccentricity of the centers about which the handle and the bag pivot.

By attaching the strap in this manner, it serves two functions, first, as a means of bag-suspension immediate the edge of the bag head which is the preferred point of attachment when the bag is inflated, and, second, as a means of bag suspension from approximately the center of the bag-head when the bag is deflated and the handle is in inoperative position; substantially vertical.

I claim:

1. In a dust-collecting bag having a head, a slider strap secured to the bag head, the ends of the strap being secured in spaced relation substantially diametrically of the bag head, the central portion of the strap being free.

2. In combination with a dust-collecting bag having a head, a strap secured to the head thereof, one end of the strap being se-

cured at substantially the center of the head, the other end being secured substantially at the periphery thereof.

3. In combination with a dust-bag, a suspension-slider strap, the ends thereof being attached to the bag in spaced relation.

4. A dust bag having side walls and a head, a single means having its ends secured

to the bag head in spaced relation whereby the bag may be suspended from a point adjacent the periphery of said head or from another point of said head. ¹⁰

Signed at Canton in the county of Stark, and State of Ohio A. D. 1922.

MAX C. RICHARDSON.
